FIG. 11

FIG. 12

FIG. 1 is a side elevational view of a powered sweeping machine as viewed from the right side thereof embodying my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view of a modified form of the powered sweeping machine embodying my new design as viewed from the right side thereof;

FIG. 8 is a left side elevational view thereof;

FIG. 9 is a front elevational view thereof;

FIG. 10 is a rear elevational view thereof;

FIG. 11 is a top plan view thereof; and

FIG. 12 is a bottom plan view thereof.

This application is a continuation application of my two co-pending design patent applications, Serial Nos. D. 77,207 and D. 77,208, both filed October 30, 1963, and now abandoned, for Electric Power Sweeping Machine and Power Sweeping Machine with Filter, respectively.

I claim:

The ornamental design for a powered sweeping machine, as shown and described.
